A. LANGLAIS.
GLASS BEVELING MACHINE.

No. 408,726.

Patented Aug. 13, 1889.

Technical drawing of a mechanical device, labeled 'Fig. 1' in the top left corner. The drawing shows a complex assembly of mechanical parts, including a flywheel at the top right, a central vertical shaft, and various gears and linkages. The parts are labeled with letters and subscripts: 'A', 'B', 'C', 'D', 'E', 'F', 'G', 'H', 'I', 'J', 'K', 'L', 'M', 'N', 'P', 'Q', 'R', 'S', 'T', 'U', 'V', 'W', 'X', 'Y', 'Z', and 'a', 'b', 'c', 'd', 'e', 'f', 'g', 'h', 'i', 'j', 'k', 'l', 'm', 'n', 'o', 'p', 'q', 'r', 's', 't', 'u', 'v', 'w', 'x', 'y', 'z'. The drawing uses a combination of solid and dashed lines to represent different components and their assembly. The flywheel is labeled 'T' and is mounted on a vertical shaft. Various gears and pulleys are labeled with letters and subscripts, such as 'A', 'B', 'C', 'D', 'E', 'F', 'G', 'H', 'I', 'J', 'K', 'L', 'M', 'N', 'P', 'Q', 'R', 'S', 'T', 'U', 'V', 'W', 'X', 'Y', 'Z', and 'a', 'b', 'c', 'd', 'e', 'f', 'g', 'h', 'i', 'j', 'k', 'l', 'm', 'n', 'o', 'p', 'q', 'r', 's', 't', 'u', 'v', 'w', 'x', 'y', 'z'. The drawing is a detailed technical illustration of a mechanical system, likely a printing press or similar device, showing the relationships between its various components.

A. LANGLAIS.
GLASS BEVELING MACHINE.

No. 408,726.

Patented Aug. 13, 1889.

UNITED STATES PATENT OFFICE.

ALONZO LANGLAIS, OF MONTREAL, QUEBEC, CANADA, ASSIGNOR OF ONE-HALF TO A. RAMSAY & SON, OF SAME PLACE.

GLASS-BEVELING MACHINE.

SPECIFICATION forming part of Letters Patent No. 408,726, dated August 13, 1889.

Application filed November 30, 1888. Serial No. 292,250. (No model.)

To all whom it may concern:

Be it known that I, ALONZO LANGLAIS, of the city of Montreal, in the district of Montreal and Province of Quebec, Canada, have invented certain new and useful Improvements 5 in Glass-Beveling Machines; and I do hereby declare that the following is a full, clear, and exact description of the same.

This invention relates to that class of machines in which a movable table or carrier is used for bringing the glass against the face of a revolving grinding-disk in stationary bearings, and may be broadly described as consisting of a frame-work upon the upper 10 side of which tracks are placed for a carriage mounted on wheels to run along, from this carriage being suspended the table (capable of adjustment at differing angles) for holding the glass, and at a point about midway of the 15 frame being situated the grinding-disk, the whole being provided with suitable running-gear, reverse and stop-motion mechanism, the arrangement and details of construction of the parts which constitute the invention obviating many serious difficulties hitherto experienced in the operation of such machines.

For full comprehension of the invention reference must be had to the annexed drawings, in which—

30 Figure 1 is a view of the front side of the machine; Fig. 2, a plan, and Fig. 3 an end view, of same; Fig. 4, a detail of reversing and stop-motion mechanism; and Figs. 5, 6, and 7 details of grinding mechanism.

35 Similar letters of reference indicate like parts.

A is the frame-work, of any suitable construction and rectangular in form.

40 *a a* are tracks placed along the top of the upper longitudinal timbers, and B is a carriage or traveler mounted on wheels moving on such tracks.

B' is a rack placed in the center of the top of the carriage and extending longitudinally 45 its whole length.

B² B² are hangers secured centrally at each end of the carriage B, and *c c* are blocks working in guides in such hangers and carrying the ends of the shaft C', on which table C is mounted, these blocks being raised

and lowered by the operation of screws *b b*, threaded through them.

D is a longitudinal shaft, connected with each screw *b* by miter-gearing *d*, as shown, which can be rotated by means of a crank or 55 key fitted on one of its ends extended for the purpose, as shown at *d'*.

The table C is a rectangular open-work frame constructed with a view of allowing all dust to fall through it. It is not borne exactly equidistant from both sides in order that as large a proportion as possible of its surface may be brought to the front side, an adjustable counterpoise G being arranged on the opposite side to counterbalance such preponderance, and also to secure the necessary pressure against the face of the grinding-disk.

In adjusting the table from the horizontal position to an angle the shaft D is rotated in 70 the required direction, the rotation of the screws *b* raising the blocks *c c*, and as the front of the table is held down by a stop *a'* on the frame-work A, the table is tilted on its axis C', and when the desired position is secured, the gravity-weight is adjusted to balance the weight of the glass and the extra preponderance mentioned and to secure the necessary pressure.

The grinding-disk F is illustrated clearly 80 in Figs. 5, 6, and 7, the first of these being a plan view and Figs. 6 and 7 sections taken, respectively, on lines *x x* and *z z*, Fig. 5. It will be seen that it has an annular beveled grinding-face F', the bevel rendering the disk 85 deeper at the inner periphery of such grinding-face than at the outer. In order that the disk may revolve in such a way as to bring but a very small portion of the annular abrading-face in contact with the glass at one time, 90 its axis, in addition to being set at the angle required for beveling, is caused to lean or be tilted toward the side from which the glass approaches, in order that, as shown, no cutting will take place except at the point P— 95 *i. e.*, instead of in the usual saw-like fashion a segment of the disk in the axis of the same at right angles to the plate bearing upon this latter, the whole depth of the grinding-face, taken in radial section at a certain point, 100

comes almost parallel with the edge of the plate before beginning to cut, as shown in Figs. 5 and 7. In fact, the cutting is performed pretty much in the same manner as if a rapidly-moving chisel were placed at a certain angle and a strip of material passed along so that the chisel would cut through from the top side to the front edge, and thus produce the bevel. Such an arrangement secures an immediate clearance of the portion, however small, previously ground. The disk has a hub F^2 , and is mounted on a shaft e , carried in suitable bearings at such an angle as will secure for the disk the proper position relatively to the table when set horizontally, to allow a variation of bevel on the glass, say, from one to thirty degrees, the greater angle being obtained while the table is horizontal and the less when it is brought almost parallel with the disk.

It is apparent from Figs. 6 and 7 that the shaft e of the grinding-disk to secure the beveling angle and the shortness of contact of the disk with the glass must be set at a compound angle, and the shaft in Fig. 6 shows the inclination of the shaft out of the vertical to secure the beveling-angle, and the dotted line 1 1 in Fig. 7 indicates the departure of the shaft-axis from the vertical to secure the shortness of contact, the divergences being at right angles to each other, and resulting in the compound angle required.

A simple way of securing the tilt, as in Fig. 7, is to insert wedges beneath the bed-plate of the grinder at the right-hand side, looking at Fig. 1, or any other means of adjustment might be used.

The beveling of the grinding-face is of course to compensate for the second tilt given to the disk, and to bring the radial lines of such face, when in contact with the plate, parallel or nearly so, thereto. One of the bearings for the shaft e is situated below the grinding-disk, and if it were not protected from the dust and ground glass which fall down in its vicinity the action of the shaft would be materially affected. I guard against this by casting a hub or shield H on the shaft, recessed to fit over the upper end of the bearing, as shown in Fig. 3. I am also able by this arrangement of the disk grinding with its under face to place a cover H' above it, so as to protect the upper journal. The disk-shaft can be rotated by any system of belts and pulleys or gearing desired, this forming no part of my invention, and the sand and water usually employed to assist the grinding may be conducted to the desired point in any suitable way.

Reverting to the table C , C^2 C^2 are buttons, which may be turned up so as to form extra surface, against which the edge of the glass can be pressed when being placed on the table, so as to insure its correct position thereon, and afterward turned down, leaving it with no other gage than the projecting edge of the strips c' , extending about a third of the thick-

ness of the glass, so as not to interfere with the grinding.

c^2 c^2 are the necessary adjustable holdfasts required, consisting of wooden slats with thumb-screws for tightening tongues sliding in dovetailed grooves, as is well understood.

c^3 are loose slats for the glass to rest on.

To secure the reciprocal action of the table, a driving-shaft J is carried across the top of the frame in suitable bearings $J' J'$, attached to side timbers $A' A'$, set up on top of the frame proper, and a pinion j , loosely mounted on such shaft, intermeshes with the rack B' on the carriage B .

Two loose pulleys $K' K^2$, with a tight one K^3 intervening, are mounted on the shaft J , and two driving-belts running in opposite directions are taken around them, their positions being, while the machine is at rest, one on the tight pulley and the other on one of the loose pulleys, so that the shaft is revolving in the direction of the belt on the tight pulley; but as the pinion is mounted loosely on it the carriage is not operated. To connect the pinion with the shaft, when it is desired to operate the carriage, a clutch L is used, worked by the hand-lever L' , through any ordinary connections.

To start the machine, the clutch is operated to connect the pinion with the shaft, and upon whichever belt is placed the tight pulley will depend the direction of movement of the carriage and table, which will always be the same as that of such belt. The means for so placing the belts will be described farther on.

As the edges of the glass plates to be beveled are of various lengths, I employ a variable cut-off consisting of a movable dog or detent M , arranged to slide along the top of one of the longitudinals of the carriage B and be secured at any required point, and in connection with apparatus for placing the driving-belts, as before mentioned, this consisting of lever N , having arm N' connected with slider-bar N^2 , carrying hoop n for encircling the belts. I pivot on the lever N , so as to work vertically and be moved by such lever in its horizontal movement, an additional lever O , carrying on one end a pin O' , projecting downwardly through a slot in the lever N , so as to be in the way of the dog M , and by the onward movement of such dog be caused to press against the side of the slot and move the lever N , so as to dispose the belts in positions directly opposite to those previously occupied by them—viz., the belt which was on the tight pulley off it onto a loose one, and the belt previously on the loose pulley onto the tight one, thus reversing the direction of movement of the carriage so soon as the end of the glass is reached and causing it to travel back to its original position.

Q is an additional hand-lever connected with lever N , whereby the position of the belts may be easily controlled by hand in the event of a portion of the glass being discovered to

be harder than the balance, and therefore requiring regrinding.

It will be seen that by the construction of my machine—viz., with the grinding apparatus placed below the level of the traveling mechanism—no interruption will occur to the working by any portion of the abrading substance—dust, &c.—getting into the machine, and that the bearing-surfaces of the grinding apparatus are thoroughly protected against grit, &c.

What I claim is as follows:

1. In a glass-beveling machine, the combination of frame-work supporting tracks, a movable carriage adapted to travel along same, hangers suspended from such carriage, a table carried in such hangers, on which glass plates are placed, a grinding-disk in stationary bearings, driving mechanism and automatic reversing mechanism controlling same for giving said carriage reciprocal motion, whereby the glass plates are subjected to the action of such disk.

2. In a glass-beveling machine, the combination of frame-work supporting tracks, a movable carriage adapted to travel along same, hangers suspended from such carriage, a table supporting the glass plates carried axially in such hangers and being capable of adjustment at various angles, screws for securing such adjustment, a grinding-disk in stationary bearings, and driving mechanism and automatic reversing mechanism controlling same for giving the aforesaid carriage reciprocal motion, whereby the glass plates are subjected to abrasion from the under surface of said disk.

3. In a glass-beveling machine, the combination, with a frame-work supporting tracks, a movable carriage traveling on same, and hangers suspended from said carriage, a shaft carried in movable blocks capable of adjustment in said hangers, and screw mechanism

for obtaining such adjustment, of a table for supporting the glass plates mounted eccentrically on such shaft, and an adjustable counterpoise adapted to counterbalance the preponderance of table on one side of its axis and secure the pressure of the glass plates against the face of the grinding-disk.

4. In a glass-beveling machine, the combination of a frame A, tracks a a, carriage B, hangers B², and blocks c c, working in same, screws for adjusting said blocks, shaft C', carried by said blocks, table C, mounted on such shaft, driving mechanism and automatic reversing mechanism for controlling same for imparting to said carriage reciprocal motion, and means for governing such reciprocal motion, all substantially as herein shown and described.

5. In a glass-beveling machine, the combination, with carriage B, driving mechanism and automatic reversing mechanism controlling same for imparting to such carriage reciprocal motion, and hand-lever for governing such motion, of cut-off mechanism, substantially as shown and described, consisting of dog M, lever O, and pin O' on same.

6. In a glass-beveling machine, a grinding-disk with grinding-face on its under side, a rotary shaft and bearings carrying such shaft at an angle both to the longitudinal and transverse axes of the machine, the grinding-face on the under side of such disk being beveled to compensate for the inclination of the shaft out of the transverse vertical axis.

7. In a glass-beveling machine, the combination, with the rotating shaft e, mounted in bearings, of recessed shield H cast on it, as and for the purpose described.

ALONZO LANGLAIS.
